UNITED STATES PATENT OFFICE.

JOHN P. CONNOR, OF BOSTON, MASSACHUSETTS.

PASTRY-OVEN.

SPECIFICATION forming part of Letters Patent No. 398,380, dated February 26, 1889.

Application filed June 16, 1888. Serial No. 277,316. (No model.)

To all whom it may concern:

Be it known that I, JOHN P. CONNOR, a citizen of the United States, residing at Boston, in the county of Suffolk and State of Massachusetts, have invented a new and useful Improvement in Pastry-Ovens, of which the following, taken in connection with the accompanying drawings, is a specification.

The object of my invention is to produce a pastry-oven in which the heat is equally distributed through its center, and in which the contents of one half of the oven can be seen without admitting cold air into the other half.

The invention consists in arranging in the center of the oven a radiator fitted with a partition and a pipe communicating between the fire-pot and the flue, said pipe being provided with a damper and holes communicating with the interior of the radiator, so that when the damper is closed the heat and products of combustion are caused to pass through the radiator, thereby bringing the heat to the front part of the oven, and should the oven be too hot, by opening the damper the heat can pass up the pipe directly to the flue.

Referring to the accompanying drawings, Figure 1 represents a perspective view of a pastry-oven embodying my invention. Fig. 2 is a longitudinal vertical section through the same. Fig. 3 is a transverse vertical section taken through the radiator.

The top A, back B, and sides C of the oven consist of a double casing formed of metal plates *a b*, with an air-space, D, between them. The front E consists of a single metal plate, and is provided with feed and ash-pit doors *c d* and registers *e*. All of the above parts are old and of well-known construction.

In the center of the casing I place a radiator, F, consisting of two vertical plates, *f f'*, with a space of a few inches between them, and through the radiator at the rear is fitted a pipe, G, that communicates at its lower end with the fire-pot or stove K, and at its upper end with the flue. In this pipe are formed two openings, *g g'*, and in the radiator is secured a partition, H, sloping upward and extending from the pipe G to nearly the front of the oven.

J is a damper fitted in the pipe G, the rod

of which extends out through the front, as shown.

By the radiator F the oven is divided into two compartments, L M, or, as it were, distinct ovens, although they are both heated by the same fire; and on each side of each compartment I secure angle-irons *m m*, upon which the shelves *n* rest. The compartment M in Fig. 1 I have shown with the two upper shelves removed. Each of the compartments L M are closed by a separate door, N N', so that the contents of one compartment may be inspected without admitting cold air into the other compartment.

In operation, when a fire is first started, the damper J is opened, as shown in Fig. 3, and the smoke and products of combustion pass directly up the pipe G in the direction of the arrows marked 1; but when the fire is clear the damper is closed and the heat then passes through the radiator in the direction of the arrows marked 2, the partition H causing the heat to pass to the front of the oven. By this arrangement the heat is more evenly diffused, and consequently the oven is more evenly heated than with ovens of ordinary construction.

Should the oven become too hot, then the damper J is opened and the heat will pass directly up the pipe G, very little, if any, passing through the radiator. The heat of the oven is also regulated by the ventilators *e e*, and by the dampers in the ventilating-pipes P, that pass from the compartments L M to the flue.

Pastry-ovens of ordinary construction can be easily and cheaply fitted with radiators constructed according to my invention, and although I have shown and described the oven as adapted to be heated by coal they can be equally well adapted to burn wood.

What I claim as my invention is—

1. In combination with a pastry-oven, the central vertical radiator, F, provided with the pipe G, having openings *g g'* and fitted with a damper, J, and the partition H, whereby the heat entering the radiator through the opening *g* is caused to pass to the front of the oven and thence back and through the opening *g'* to the flue, substantially as set forth. 100

2. A pastry-oven divided by a central vertical radiator, F, into two compartments, L M, closed by separate doors, N N', in combination with the smoke-pipe G, having openings 5 g g' and damper J, and the fire-pot K, substantially as shown and described.

In testimony whereof I have signed my name

to this specification, in the presence of two subscribing witnesses, on this 17th day of May, A. D. 1888.

JOHN P. CONNOR.
